BALL VALVE SAFETY PILOT BURNER

Frank R. Higley, Cleveland Heights, Ohio, assignor, by mesne assignments, to Affiliated Gas Equipment, Inc., Cleveland, Ohio, a corporation of Delaware

Application August 18, 1944, Serial No. 550,176

1 Claim. (Cl. 158—117.1)

1 This invention relates to improvements in valves, more particularly a safety valve for a burner control thermally responsive to the flame from a pilot which is disposed in or upon a pilot arm that is rigid with the valve casing. In some of its aspects the invention constitutes an improvement over my copending application, Serial No. 533,309, filed April 29, 1944.

One of the objects of the invention is the provision of a valve casing so chambered as to provide a flow path characterized by a single bend which is disposed in a plane generally perpendicular to the pilot arm, with a valve of a character such that it will not interfere with the free flow of gas along that path.

Another object is the provision of a unit for the purpose stated, in which the valve shall occupy a relatively small space, having small dimensions particularly in the vertical direction and in the direction away from the oven wall.

Still another object is the provision of thermally responsive valve actuating means such that when it is heated and consequently in weakened condition, it is substantially unloaded.

Other objects and features of novelty will appear as I proceed with the description of that embodiment of the invention which, for the purposes of the present application, I have illustrated in the accompanying drawings, in which

Fig. 1 is a plan view of a unit embodying the invention.

Fig. 2 is an elevational view of the same.

Fig. 3 is a bottom plan view of the same.

Fig. 4 is a fragmental side view of the unit inverted, looking in the direction of arrow 4 in Fig. 3.

Fig. 5 is an end view looking in the direction of arrow 5, Fig. 1.

Fig. 6 is a vertical sectional view taken substantially on the line 6—6 of Fig. 2, illustrating the automatic safety valve and a portion of its actuating means.

Figs. 7 and 8 are sectional views, transverse to that of Fig. 6 and taken substantially on the lines 7—7 and 8—8, respectively, of Fig. 6.

Figs. 9 and 10 are detail sectional views, taken substantially on the lines 9—9 and 10—10, respectively, of Fig. 1, and

Fig. 11 is a horizontal sectional view of the valve taken substantially on the line 11—11 of Fig. 5, showing the throw of the ball engaging crankarm between valve closing and valve opening positions.

The construction disclosed comprises two main parts, a valve casing 15 and a pilot arm 16. The

2 pilot arm is preferably cast integral with the base 17 of the casing, the latter including also a cover 18. The base 17 of the casing has a bottom inlet opening 19 therein which may be threaded or otherwise constituted to receive a gas supply pipe or tube. The cover 18 has an end outlet opening 21 threaded or otherwise formed to receive a pipe or tube leading to a main burner, not shown. The axes of the two openings 19 and 21 in the illustrated embodiment lie in the same plane, which is preferred, but a slight offset of one axis with respect to the other would be within the spirit of the invention.

The base 17 and the cover 18 are suitably secured together with a high temperature gasket 23 therebetween. The securing means may consist of three threaded fastenings 24, 25 and 26 extended through smooth holes in the base and received in threaded holes in the cover, the fastening 24 being disposed at the end of the casing opposite the outlet opening 21 and the fastenings 25 and 26 being disposed at the sides of the casing near the outlet opening. The three point bearing of these fastenings upon the casing elements is, of course, desirable for effecting a good seal. Furthermore, the fastenings when thus disposed are entirely out of the way, the single one 24 being at the end of the casing outside the path of flow of gas therethrough, and the two fastenings 25 and 26 being at the sides of that path where they do not constrict flow.

The inlet opening 19 is connected with the valve chamber 27 by a bore 28, at the top of which there is a circular valve seat 29 in which a ball valve 30 normally rests for cutting off the flow of gas between the inlet and outlet openings. An important feature of the invention is the arrangement of parts such that the valve may be opened by a slight movement upwardly and to the left, as seen in Fig. 6, in other words away from the openings 19 and 21. Because of this arrangement a minimum movement of the ball affords a full opening of the valve with a single bend only in the path of flow.

45 A further feature of the invention is that the actuating means within the chamber 27 is disposed at the bottom of the chamber in the angle between the inlet and outlet openings where it substantially clears the path of flow of the gas. 50 As shown, it comprises a crankshaft 31 oscillatable in a bore in the base 17 of the casing and a head 32 having a beveled shoulder engaging a correspondingly beveled seat at the top of the bore. These beveled surfaces are finished to effect a 55 gas-tight seal. In the head 32 there is mounted

a crankarm 33, the end of which is adapted to contact ball 30 to effect opening movement thereof, by its own movement, toward and approximately to the center of the valve seat opening 20, the crank arm 33 moving in a plane closely adjacent that of this opening.

When the valve is closed, the arm 33 extends somewhat to one side of the plane defined by the axis of crankshaft 31 and the center of the ball, but in opening the valve, the arm 33 is caused to move toward that plane and in the fully opened position it lies in that plane. Thus in the open position the load of the ball is directly down upon the crankarm 33, assisting in maintaining the seal around the top of shaft 31. There is then no horizontal component acting to force arm 33 in one direction or the other, and therefore no load is transferred to the thermally responsive member by which the shaft 31 is turned, which member is weakest when heated as it must be when the valve is open.

At the junction between the casing 17 and the pilot arm 16 there is an enlargement in which is formed a threaded opening 35 for the reception of a tube through which pilot gas is supplied. Opening 35 communicates with a laterally extending portion 37 of a cored-out passage 38 running lengthwise of the arm. The other end of the arm has lateral extensions 39 and 40, the extension 39 having a laterally projecting branch passage 41 which may be threaded to receive a screw 42. This disposition of the branch part 37 of the pilot gas passage in the same plane with the branch part 41 has the manufacturing advantage that in casting the pilot arm the core for the gas passage therethrough may be supported in core prints disposed in the same plane. A branch passage 43 at the far end of the passage 38 supplies gas to ports 44 and 45. Ports 46 supply gas for heating a thermally responsive member 47 which is mounted upon the extension 39 by means of the screw 42. Other suitably disposed ports, such as the ports 48 of Fig. 1, may be employed for communicating flame from the ports 44 or 45 to the ports 46. The thermally responsive member 47 is of the compensated laterally deflecting type and deflects away from the pilot arm 16, subject to pilot flame, to actuate the bell crank parts 31, 33 and 60 in valve opening direction, which is counterclockwise in Fig. 3 and clockwise in Fig. 11. A member of this kind suitable for the purpose is fully disclosed and claimed in my copending application Serial No. 542,657, filed June 29, 1944.

A port 50, Fig. 3, communicating with passage 38 near valve casing 15, may be ignited by any convenient means, as for example by flash from another flame conducted through suitable flash tubing connected with an opening 51 surrounded by a flange 52 struck up from a sheet metal cover 53 mounted on the pilot arm. It is within the spirit of the invention to ignite the gas from port 50 by any other suitable means, however, including electrical means.

Cover 53 has a bifurcated portion 54 which extends beneath the head of screw 42 for supporting the cover at one end, its opposite end being attached to the pilot arm 16 by a screw 55. The cover projects to one side of the pilot arm and has a downturned flange for the protection of the thermally responsive member 47 and as a shield for that member against heat radiated from the oven burner. The cover also projects laterally in the opposite direction, where it has a downturned and inturned flange to constitute a flash

tube through which flame is flashed from port 50 to flash port 44, see Figs. 9 and 10. Port 45 is an igniting port for an oven burner, not herein shown. A suitable bracket 56 varying in size and form for installation in different ranges, has a perforated end disposed between the thermally responsive member 47 and the bifurcation 54 of the cover and held by the screw 42. In addition to its function as securing means for the thermal member 47, the bracket 56 and the cover 53, screw 42 serves as a plug or closure for the branch core passage 41.

Thermally responsive member 47 is shown in the drawing in its unheated condition. At its free end, which extends beneath the base 17 of the flange casing, it may have an angularly disposed extremity 60 perforated to receive an arm 61 mounted in the exposed portion of the crankshaft 31. The arm 33 within the valve casing, the shaft 31, and the arm 61 outside the casing thus constitute bell crank means effective through the casing wall. The free end of the member 47 is prevented from moving downwardly by its connection with arm 61. It is prevented from moving upwardly, and from moving the crankshaft 31 upwardly to a like extent, by a narrow depending flange 62 on a small sheet metal bracket 63 which is attached to the base of the casing by the head of screw 26. The heads of screws 24 and 25 may be similarly employed for screwing to the base 17 a bracket 64 of any suitable form and size for attachment of the casing to a range. A second relatively wider depending flange 65 on the small bracket 63 protects the free end of member 47, including the extremity 60. A downwardly projecting guard 66 formed integral with the base 17 protects the lower end of crankshaft 31, while this guard and the flange 65 together protect the arm 61 of the crank.

A projection 67 extending downwardly from the inner surface of the cover 18 limits the upward movement of ball 30, while permitting a tilting movement of the ball in a diagonal direction upwardly and toward the left, as viewed in Fig. 6. The projection 67 is especially useful in preventing movement of the ball while the valve is being handled or transported.

The operation of the unit will be clear to those skilled in the art, particularly when taken in connection with the disclosures in my copending applications Serial No. 533,309 and Serial No. 542,657, above mentioned. In the cold position of the thermally responsive member 47 the ball 30 is seated and the free end of the actuating arm 33 is adjacent but out of engagement with the ball. It then stands outside of the plane defined by the center of the ball, or the center of its seat, and the axis of shaft 31. When the member 47 is heated by flames from ports 46 it swings away from those ports and turns shaft 31 in the clockwise direction, as viewed in Fig. 11. The end of the arm 33 then engages the ball, the point of contact gradually moving toward the plane mentioned above. When this point of contact has arrived in that plane, as shown in broken lines in Fig. 11, the valve is fully opened, the ball having been tilted upwardly upon the far edge of its seat, that is, away from the end opening 21 of the casing. The action of the arm 33 relative to the ball and that part of the seat about which it tilts is like that of a toggle. When the open position is reached, the load due to the weight of the ball is transmitted along the length of the arm 33 and downwardly upon the arm. Hence, in the heated condition

of the thermally responsive member there is no tendency for the weight of the ball to turn shaft 31, and no force is transmitted to the heated thermal member which is then in weakened condition. Furthermore, the weight of the ball tends to depress crankshaft 31 and thereby hold the beveled surfaces between that shaft and the casing in sealing engagement. The construction disclosed provides a flow path for gas through the casing from the inlet to the outlet, which has but a single bend and is free of any obstruction since the ball actuating mechanism within the chamber 27 hugs the bottom thereof and does not extend upwardly into the flow path.

It will be appreciated that this entire unit must be subjected to high temperature, since it is to be located entirely within an oven. At the same time, the flow of gas through the chamber 27 tends to cool the interior surfaces of the casing. The condition of a highly heated outer surface and a cooled inner surface places a heavy strain upon the metal of the casing, having a tendency toward warpage of the casing. The very simple form of my casing, however, having no internal webs or other protruding parts, minimizes warpage.

Having thus described my invention, I claim:

In apparatus for the purpose described, a main burner valve casing having a horizontally disposed valve seat and being chambered to provide a flow path characterized by a bend in an upright plane between inlet and outlet openings by way of the opening of said valve seat, a ball valve for said seat, a pilot arm extending laterally from said casing perpendicularly to said plane and having pilot burner means, a laterally deflecting thermally responsive member mounted on said arm adjacent the end thereof remote

from said casing to be responsive to said pilot burner means, said member extending from said end alongside said arm toward the casing, bell crank means mounted in said casing for movement about an upright axis and having an arm arranged outside said casing for actuation by said thermally responsive member, and an arm arranged within said casing for movement in a plane adjacent the plane of said valve seat for end engagement with said valve to effect opening movement thereof in a direction away from said openings.

FRANK R. HIGLEY.
